UNITED STATES PATENT OFFICE

REGNIER EICKWORTH, OF ESSEN, GERMANY

GAS BURNER

Application filed August 24, 1921, Serial No. 494,974, and in Germany November 11, 1919.

The following applications have been filed in Germany, November 11, 1919, now Patent No. 327,094, Germany, January 16, 1920, now Patent No. 336,631, Germany, August 13, 1920, 5 now Patent No. 422,242, Germany, September 27, 1920, now Patent No. 336,632, England, two on Oct. 28, 1920, now Patents Nos. 157, 880 and 153,897, France, November 9, 1920, now Patent No. 527,073, Austria, November 10 2, 1920, Belgium, November 5, 1920, Luxembourg, November 3, 1920, Poland, March 29, 1921, Czecho-Slovakia, March 25, 1921.

My invention relates to gas burners for industrial furnaces. The burner is of the type 15 in which the gas and the air to be admixed with the gas are ejected from rotary impellers, and it is an object of my invention to improve a burner of this general type. To this end, instead of the usual coaxial arrangement of the impellers in which the gas and the air are discharged in coaxial layers, and deflection by the wall of the combustion chamber is relied upon for mixing and churning the two constituents, I provide an impeller having a single annular row of vanes 20 to which air and gas are supplied through separate passages, and are mixed in the impeller. It will be understood that a much more intimate mixture of the media is effected in this manner, as the streams of air and gas are broken up and thoroughly churned by the vanes immediately after they have issued from their respective passages.

The relative arrangement of the gas and 35 air passages on the one hand, and the impeller vanes on the other, may be modified in various ways. For instance, the gas and air passages may be so arranged that the streams of air and gas issue from such passages in axial relation to the impeller. This type may be 40 modified by either arranging the passages in two coaxial rows, each row comprising passages for one medium only, or by providing a single row of passages, or the passages may be so arranged that the issuing streams are 45 in radial relation to the impeller.

Preferably, one of the media, for instance the air, is supplied under pressure so that it will impart rotation to the impeller, but if desired a separate supply of compressed air

may be provided for imparting rotation to the impeller, and the bulk of the air is then drawn into the impeller by suction.

To prevent the formation of explosive mixtures in the impeller it may be desirable to provide auxiliary air passages in addition to those normally provided, so that only a certain percentage of the air is mixed with the gas in the impeller, and determined so as to prevent the formation of an explosive mixture, while the additional air for complete combustion is introduced through the auxiliary air passages. These passages may be arranged intermediate the rim and the boss of the impeller and, if desired, may be combined with the injecting vanes.

In the accompanying drawings, several burners embodying my invention are illustrated diagrammatically by way of example.

In the drawings

Figs. 1-3 illustrate a burner having two coaxial rows of gas and air passages,

Figs. 4 to 7 illustrate a burner having a single row of alternating gas and air passages,

Figs. 8 to 10 illustrate a burner having a separate supply of compressed air,

Figs. 11 and 12 illustrate a burner having separate air passages in the impeller, and

Figs. 13 and 14 illustrate a burner in which a fuel supply is combined with the separate supply of compressed air.

More particularly Fig. 1 is a vertical section through the casing of a burner at right angles to the axis of its impeller, in which the gas and air passages are arranged in two coaxial rows, and such rows are so placed with respect to the impeller that the streams of gas and air issue in axial direction.

Fig. 2 is a section on the line II-II in Fig. 1,

Fig. 3 is a section corresponding to Fig. 2, but showing gas and air passages from which the streams issue in radial direction with respect to the impeller.

Fig. 4 is a section corresponding to Fig. 1, and

Figs. 5 and 6 are sections on the lines V-V and VI-VI in Fig. 4, respectively,

Fig. 7 is a development showing a portion

of the impeller and the gas and air passages alternating in pairs.

Fig. 8 is a section through the casing of a burner having a separate supply of compressed air, the section being taken on the axis of the impeller,

Fig. 9 shows a portion of the impeller vanes and the gas and air passages developed,

Fig. 10 is an end elevation of the burner, 10 viewed from the left in Fig. 8,

Fig. 11 is a section corresponding to Fig. 1, Fig. 12 is a section on the line XII—XII in Fig. 11,

Fig. 13 is a section corresponding to Fig. 8, 15 and

Fig. 14 is a development corresponding to Fig. 9.

Referring now to the drawings, in all the figures 1 is the casing of the burner, 2 is the 20 impeller, 3 is a bearing secured to the casing in which the impeller shaft is carried, *a* are the gas passages, *b* are the air passages, *c* is the rim of the impeller 2 on which its vanes are secured, *f* is an air conduit and *e* is a gas 25 conduit, said conduits being connected respectively with the gas and air passages *a* and *b*.

Referring now to Figs. 1 and 2, the gas 30 passages *a* and the air passages *b* are arranged in two coaxial rows in front of the impeller 2 and the streams of gas and air issue from such passages axially with respect to the impeller. At the ends of the passages the issuing streams are entrained by 35 and thoroughly churned in, the vanes of the impeller. The flame is projected into a combustion chamber 4 with a refractory lining *g*.

Referring now to Fig. 3, the arrangement is 40 substantially the same as described with reference to Figs. 1 and 2, but instead of passages arranged in axial direction, this burner is equipped with radial passages *a'* and *b'* for gas and air, respectively, and the impeller 2' is designed with a flange extending 45 beyond its rim *c'*, the vanes being supported by the flange and the rim instead of extending freely from the rim *c* as shown in Fig. 2.

The embodiment illustrated in Figs. 4 to 7 is preferred. Here, as will be seen in Fig. 50 7, the gas and air passages *a*, *b* are arranged alternately in pairs in a single row. It will be understood that in this manner an even more thorough mixing and churning action will be effected as the streams of gas and air 55 issuing from the passages *a* and *b* are intercepted and entrained by the vanes of the impeller throughout their width whereas in the burner illustrated in Figs. 1, 2, and 3 the streams form separate layers adjacent the 60 inner and the outer rims of the impeller.

Referring now to Figs. 8 and 9, the gas and air passages *a* and *b* are shown arranged alternately in pairs as shown in Fig. 7, gas 65 being supplied through a pipe 5 at the top of the casing 1, and air entering through the

open front end 6 of the casing. *i* is a pipe through which compressed air is supplied to two nozzles which are arranged intermediate the alternating gas and air passages *a*, *b*. Obviously, any number of pipes *i* may be provided and I am not limited to the alternating arrangement shown. In Fig. 9 the distribution of the media in the vanes of the impeller *c* is indicated by sectioned rectangles, the horizontally sectioned rectangles indicating layers of gas, and the cross-hatched sections indicating layers of air.

The velocity imparted to the entrained media by the impeller is such as to prevent backward ignition. In order, however, to absolutely eliminate any possibility of backward ignition which might occur if the velocity decreases for some reason or other, the percentage of air which is supplied to the vanes *c* may be so determined as to prevent the formation of an explosive mixture. A burner in which this is effected is illustrated in Figs. 11 and 12, where the impeller 2 is provided with auxiliary air passages *i'* through which part of the air from the conduit *f* flows directly into the combustion chamber 4, while the balance issues from the passages *b*, as described.

The arrangement of the burner illustrated in Figs. 13 and 14 is generally similar to that 95 illustrated in Figs. 8, 9 and 10, but in this instance the pipe *i* for the compressed air is combined with a pipe *k* for injecting pulverulent fuel, powdered coal or the like, into the impeller with the compressed air.

I wish it to be understood that I do not desire to be limited to the exact details of construction shown and described, for obvious modifications will occur to a person skilled in the art.

I claim:—

1. A burner comprising a casing, a rotary impeller in said casing, a rim on said impeller, vanes on one side of said rim, and passages for gas and for air in said casing which are so arranged with respect to said vanes that each of said vanes intersects the lines of flow from the passages for gas and from the passages for air.

2. A burner comprising a casing, a rotary 115 impeller in said casing, a rim on said impeller, vanes on one side of said rim, passages for gas and passages for air, arranged alternately in said casing and so disposed with respect to said vanes that each of said 120 vanes intersects the lines of flow from the passages for gas and from the passages for air.

In testimony whereof I affix my signature.

REGNIER EICKWORTH.
